FIG. 1 is a perspective view of a pneumatic tire embodying my new design, it being understood that the full-line portion is repeated throughout the circumference of the tire shown by means of broken lines;

FIG. 2 is an enlarged fragmentary plan view of the full-line portion shown in FIG. 1;

FIG. 3 is an enlarged fragmentary side elevational view of the full-line portion shown in FIG. 1;

FIG. 4 is a sectional view taken substantially on the plane indicated by line IV-IV in FIG. 2;

FIG. 5 is a detailed sectional view taken substantially on the plane indicated by line V-V in FIG. 4; and

FIG. 6 is another detailed sectional view taken substantially on the plane indicated by line VI-VI in FIG. 4.

The dominant features of my design reside in those portions shown in full lines in the drawings.

I claim:

The ornamental design for a pneumatic tire, substantially as shown and described.
